UNITED STATES PATENT OFFICE.

AUGUST WEBER, SR., AND JOHN WEBER, OF SCHENECTADY, NEW YORK, ASSIGNEES
TO WEBER ELECTRIC COMPANY, OF SCHENECTADY, NEW YORK, A CORPORATION
OF NEW YORK.

CASE FOR INCANDESCENT-ELECTRIC-LAMP SOCKETS.

1,093,221.

Specification of Letters Patent. Patented Apr. 14, 1914.

Application filed April 7, 1908. Serial No. 425,715.

To all whom it may concern:

Be it known that we, AUGUST WEBER, Sr., and JOHN WEBER, each a citizen of the United States, residing at Schenectady, county of Schenectady, and State of New York, have invented certain new and useful Improvements in Cases for Incandescent-Electric-Lamp Sockets, of which the following is a specification.

10 The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a central, vertical, longitudinal section of our improved case for incandescent electric lamp-sockets. Fig. 2 is a top plan view of the shell with the cap removed. Fig. 3 is a bottom plan view of the cap detached. Fig. 4 is a view in perspective of a broken-away portion of the cap. Fig. 5 is a view in side elevation of the case complete.

The several figures are drawn on an enlarged scale.

30 The principal objects of the invention are to provide a more efficient interlocking mechanism for the cap- and shell-members of a case for incandescent electric lamp-sockets; to facilitate the assembling and interlocking of such parts; and to provide means for preventing relative rotation of said members when applied to each other in any relative rotative position and interlocked.

40 Other objects of the invention will appear in connection with the following description.

The invention is applicable to the telescoping members of sheet-metal cases adapted for various uses, and is particularly 45 adapted for use in the cases for incandescent electric lamp-sockets, in which preferred use it is shown in the drawings and hereinafter described.

1, is the shell of the socket preferably 50 formed of sheet-metal, and provided, if for a key socket, with the usual slot, 2, adapted to receive the shaft of the key (not shown).

The shell is provided near its upper end with a plurality of catches, 4, preferably

symmetrically disposed about the periphery 55 of the shell, and projecting outwardly therefrom. For certain purposes of the invention these catches may be of any desired form severally adapted to interlock with a seat on the cap.

We have shown as a preferred form of catch one formed by slitting the shell transversely, and outwardly displacing a portion of the body of the shell at the upper side of said slit, thereby forming a downwardly and outwardly inclined catch with a cut-metal edge. One of the catches, 4, is preferably located adjacent to the slot, 2, which may be the key-slot or a slot formed especially for the purpose of rendering the shell compressible. The cap, 3, which is also preferably formed of sheet-metal is adapted to receive within its lower end the upper end of the shell, and is provided with a continuous seat, 5, extending around its inner periphery 70 adapted to receive and interlock with the several catches, 4, in any relative rotative position of the shell and cap.

The seat, 5, is formed by a ledge or offset, 6, formed by bending an annular portion 80 of the body of the cap into a plane perpendicular to the axis of the cap, making the lower end of the cap substantially L-shaped in cross-section, said ledge, 6, being adapted to be engaged by the cut-metal 85 edges of the catches, 4, to lock the cap and shell together to prevent a relative movement of separation thereof.

The lower end, 7, of the cap is adapted to ride over the inclined surfaces of the catches, 4, until the ledge, 6, reaches the lower end 90 of the respective catches, whereupon the parts interlock with a snap action. The cap and shell can thus be assembled or applied to one another by a simple telescopic 95 movement in any relative rotative position.

By providing the seating end of the cap with the continuous annular ledge, 6, the seating portion of the cap is rendered very rigid and strong, so that the cap is adapted 100 to securely interlock with the catches on the shell.

We have shown the cap and shell provided with means for preventing their relative rotation when applied to each other telescoped 105 in any relative rotative position, and interlocked by a telescopic movement. Said means comprises one or more projections, 8,

on the annular horizontally offset portion, 9, of the cap, adapted to enter one of the seats, 10, formed in the upper edge of the shell, said projections and seats being such 5 in number and location that one or more projections, 8, will automatically enter one or more respectively of said seats when the shell and cap are applied telescopically to each other in any relative rotative position.

10 This we are able to accomplish by forming said seats by serrating certain portions of the upper edge of the shell, whereby a plurality of seats are formed adjacent to each other, and separated from one another by a

15 V-shaped tooth or projection on the upper edge of the shell. By thus forming the seats, 10, the seating of a projection, 7, in one of the seats, 10, is automatically accomplished by a simple relative telescopic movement of the case and shell, said projection riding down, and being guided to its seat by, the inclined surface of one or another of said V-shaped teeth or projections.

20 What we claim as new and desire to secure by Letters Patent is—

1. A device of the class described, comprising a sleeve and a cap having latching

mechanism to prevent separation, said sleeve having notches in its end, and said cap having a horizontally offset portion, and a member bent downwardly from said horizontally offset portion engageable with said notches to prevent relative rotation of the cap and sleeve.

2. A device of the class described, comprising a pair of case members consisting of a sleeve and a cap, one provided with a continuous annular seat and the other having projections interlockable with said seat to prevent separation, said sleeve having 35 notches in its end, and said cap having a horizontally offset portion, and a member bent downwardly from said horizontally offset portion engageable with said notches to prevent relative rotation of the sleeve and 40 cap.

In testimony whereof, we have hereunto set our hands this third day of April, 1908.

AUGUST WEBER, Sr.
JOHN WEBER.
